DESIGN FOR A LAMP OR SIMILAR ARTICLE

Howard N. Math, New York, N. Y.

Application April 25, 1946, Serial No. 128,958

Term of patent 3½ years

(Cl. D48—20)

To all whom it may concern:

Be it known that I, Howard N. Math, a citizen of United States, residing at New York city, in the county of Bronx and State of New York, have invented a new, original, and ornamental Design for a Lamp or Similar Article, of which the following is a specification, reference being had to the accompanying drawing, forming part thereof.

In the drawing:

Fig. 1 is a front view of the lamp showing my new design;

Fig. 2 is a rear view thereof; and

Fig. 3 is a cross-sectional view taken on line 3—3 of Fig. 1.

The characteristic features of my design reside in the portions shown by means of full lines in the drawing.

The design on the base portion shown in Fig. 1 is the same on the opposite side thereof. Similarly, the design on the base portion shown in Fig. 2 is the same on the opposite side thereof.

I claim:

The ornamental design for a lamp or similar article, as shown and described.

HOWARD N. MATH.
